UNITED STATES PATENT OFFICE.

ROBERT W. MASKE, OF CHICAGO, ILLINOIS.

DESIGN FOR A FLASK.

48,755.

Specification for Design.

Patented Mar. 21, 1916.

Application filed June 7, 1915. Serial No. 32,749. Term of patent 7 years.

To all whom it may concern:

Be it known that I, ROBERT W. MASKE, a citizen of the United States, residing at Chicago, in the county of Cook and State of Illinois, have invented a new, original, and ornamental Design for Flasks, of which the following is a specification, reference being had to the accompanying drawing, in which a perspective view of the design is shown.

I claim:

The ornamental design for a flask, as shown.

In testimony whereof I affix my signature, in the presence of two witnesses.

ROBERT W. MASKE.

Witnesses:

S. J. LEHRER,
H. G. BATCHELOR.
